(74) Attorney, Agent, or Firm — GREENBERG
TRAURIG, LLP(57) CLAIM

The ornamental design for a casino table with surface pattern, as shown and described.

DESCRIPTION

The sole FIGURE is a top view of a casino table with surface pattern.

The outermost broken line rectangle shows the casino table, and forms no part of the claimed design. All other broken lines show portions of the surface pattern and form no part of the claimed design

1 Claim, 1 Drawing Sheet(56)
